US00D652738S

(12) **United States Design Patent**
Boyer et al.

(10) **Patent No.:** **US D652,738 S**
(45) **Date of Patent:** **** Jan. 24, 2012**

(54) **PACKAGE WITH SURFACE ORNAMENTATION**

(75) Inventors: **Clancy Gerald Boyer**, Clarksville, OH (US); **Frank Delmar Macaulay**, Cincinnati, OH (US)

(73) Assignee: **PUR Water Purification Products, Inc.**, Cincinnati, OH (US)

(**) Term: **14 Years**

(21) Appl. No.: **29/366,987**

(22) Filed: **Aug. 2, 2010**

(51) LOC (9) Cl. **09-01**

(52) U.S. Cl. **D9/600; D9/433**

(58) Field of Classification Search **D9/600, D9/643–646, 414–415, 430, 432–433, 457; 206/457, 459.5, 461–462, 527; 229/182.1**

See application file for complete search history.

Primary Examiner — Sandra Morris

(74) Attorney, Agent, or Firm — Amanda T. Barry; Cynthia L. Clay

(57) **CLAIM**

The ornamental design of a package with surface ornamentation, as shown and described.

DESCRIPTION

The patent or application file contains at least one drawing executed in color. Copies of this patent or patent application publication with color drawing(s) will be provided by the Office upon request and payment of the necessary fee.

FIG. 1 is a top planar view of a package with surface ornamentation illustrating our new design, wherein the package is in an unfolded orientation;

FIG. 2 is a top planar view of a package with surface ornamentation illustrating our new design, wherein the package is in an unfolded orientation; and,

FIG. 3 is a top planar view of a package with surface ornamentation illustrating our new design, wherein the package is in an unfolded orientation.

The broken lines form no part of the claimed design.

**1 Claim, 3 Drawing Sheets
(3 of 3 Drawing Sheet(s) Filed in Color)**
